UNITED STATES PATENT OFFICE.

WILLIAM S. AUNGST, OF ALLIANCE, OHIO.

SUPPORTING DEVICE FOR PORTABLE TELEPHONES.

No. 895,834.

Specification of Letters Patent.

Patented Aug. 11, 1908.

Application filed October 14, 1907. Serial No. 397,386.

To all whom it may concern:

Be it known that I, WILLIAM S. AUNGST, of Alliance, in the county of Stark and State of Ohio, have invented certain new and useful Improvements in Supporting Devices for Portable Telephones; and I do hereby declare the following to be a full, clear, and exact description of the invention, such as will enable others skilled in the art to which it appertains to make and use the same.

My invention relates to an improvement in supporting devices for portable telephones, and it consists in the parts as will be more fully explained and pointed out in the claims. In the accompanying drawings, Figure 1 is a view in elevation of my improvement, showing it removably clamped to a desk. Fig. 2 is a similar view showing two telephones supporting brackets on a single standard, the support for the latter being screwed to the side of a desk. Fig. 3 is a view partly in section and partly in elevation, the standard being shown secured to a support adapted to be screwed to the top of a desk. Figs. 4 and 5 are views of the transmitter supporting clamp. Fig. 6 is a view of a standard support adapted for use on partitions. Figs. 7, 8 and 9 are views of modified forms of transmitter supporting clamps, and Fig. 10 is a view of a modified form of supporting bracket.

1 represents a metal rod or standard detachably secured at its lower end to a suitable base 2, which in Fig. 1, is in the form of a clamp adapted to be detachably secured to the top of a desk or table. In Fig. 2 the base is particularly adapted to be screwed to the side of a desk; Fig. 3 shows a base adapted to be screwed to the top of a desk and in Fig. 6 it is constructed to be screwed to a wall or partition. The standard 1 may be used in connection with these or any other preferred form of bases and is detachably secured in a socket at the upper end of the base by the screw 5.

The standard 1 may be angular or cylindrical in cross section, and of a length sufficient to permit of all reasonable and necessary vertical movement of the bracket carrying the telephone transmitter. This horizontal bracket is made in two or more sections pivotally connected, the inner one 6 of which is provided at its rear end with an enlarged hub having an opening 7 through same of a size slightly greater than the cross section of the standard 1, so as to permit of the free ver-

tical movement of the bracket on the standard, and at the same time act as a clamp for sustaining the bracket in any horizontal adjustment at which it may be placed on the standard.

As the opening through section 6 of the bracket is but slightly greater than the diameter of the standard, it will be seen that the weight of the bracket and telephone thereon, falls on the upper rear edge and the lower front edge of the wall of the opening 7, which edges, biting against the standard, act as a clamp and absolutely prevent the accidental descent of the bracket. The greater the weight of the bracket and telephone thereon, the greater the clamping action, hence in order to adjust the bracket vertically, it is necessary to grasp it and lift it sufficiently to take the weight off the clamping edges of the wall of the opening 7 through section 6 of the bracket, which leaves the latter free to be elevated or lowered, and when the bracket is released, the weight then holds its clamping edges in the position to which it has been adjusted. When so adjusted, the bracket is free to turn on the standard, but is held against any downward movement.

Section 6 is provided at its outer end with an integral head 8 provided centrally with an upwardly projecting bearing 9, having an internally threaded recess for engaging screw 10 which secures the two sections of the bracket together. Section 11 of the bracket is provided at its inner end with a hub, bored 90 to receive the bearing 9 on section 6. This hub is longer than the bearing 9, and is counterbored at its top to receive the cap 12 which is held in place by screw 10, and which locks section 11 to section 6 against displacement, without interfering with its free pivotal movement on said bearing. If there be more than two sections to the bracket, they will be connected together in the same manner. The outer section of the bracket, (in the present instance 11) is provided at its outer end with a bearing 13, in all respects like bearing 9. Mounted on this bearing 13 is one member 14 of the combined support and clamp for the telephone. This member 14 is provided with a hub mounted on bearing 13, and terminating approximately on a line with the top of the bearing. The hub and end of the member 14 adjacent thereto are cut away on top to form a seat for hub 15 of member 16 of the telephone support and clamp. This hub 15 is seated on the hub

of member 14 and is secured thereto by screw 17 which is screwed into bearing 13, the head of the screw resting in a countersunk recess in hub 15.

- 5 The two members 14 and 16 are each curved in the arc of a circle and are each provided with one or more upwardly projecting toes 18, which latter are adapted to overlap and engage the base of the telephone transmitter and hold the latter firmly on the combined support and clamp. The two members of the combined support and clamp are 10 yieldingly drawn toward each other by the spring 19, connected to each, and one member, in the present instance 14, is provided with a downwardly and outwardly projecting handle 20 which is grasped by the user when opening the jaws to receive or release the telephone. When the telephone is in 15 place and it is desired to remove same, the transmitter is grasped by one hand and the handle 20, by the other hand, and the members separated. After the base of the transmitter has been released from the toes of the 20 member 14 of the combined support and clamp, it is tilted laterally by the hand grasping same and removed.

In cases where two or more telephones are used both can be mounted on the single 25 standard as shown in Fig. 2.

With a bracket thus constructed, a telephone may be adjusted to any height most convenient for the user, and when once adjusted vertically, will remain so and may be 30 manipulated to carry the telephone out of the way, or bring it into any position most convenient for the user.

In the construction shown in Fig. 7 the transmitter supporting clamp is made in 35 two sections, each section having pivotal connection with the supporting bracket. In Fig. 7 one section 16^a is pivotally mounted on the bracket and the other 14^a pivoted to section 16^a. With this construction the 40 connection between the bracket and the clamp comes approximately under the center of the telephone, whereas in the construction shown in Fig. 8 the connection between the bracket and clamp, is at the periphery 45 of the latter.

In the construction shown in Fig. 9, the member 14^b is connected to the section 16^b, by a vertical pivot which permits of a horizontal movement of the member 14^b, and 50 the latter is made of two parts connected by a horizontal pivot 22 which permits the outer section of member 14^b to swing downwardly, it being normally retained in its upright position by the spring 21 carried by the 55 inner section of member 14^b. With this construction member 14^b can be swung outwardly sufficiently to cause the clamping

toe thereon to disengage the base of the transmitter, and then be depressed so as to permit of the free removal of the transmitter. 65

In Fig. 10, I have shown the bracket section 11 provided with a hub 23, having a bore open at the bottom and closed at the top, to receive the stud 24 on the outer end of 70 the bracket section 6, each of said studs having a peripheral groove in same to receive the end of the screws 25 which lock the sections together.

Having fully described my invention what 75 I claim as new and desire to secure by Letters Patent, is:—

1. The combination with a supporting standard and a securing base therefor, of a bracket adjustable vertically on said standard, and a combined support and clamp comprising two curved members both pivotally connected with the bracket and provided with means adapted to engage the base of the telephone, and a spring tending 80 to move said curved members toward each other.

2. The combination with a supporting standard and a securing base therefor, of a bracket adjustable vertically and pivotally 90 mounted on said standard, and a combined support and clamp comprising two curved members pivotally connected with the bracket, and provided with toes adapted to engage the base of the telephone, one member 95 of said combined support and clamp having a handle, and a spring connecting both members.

3. The combination with a bracket, of a transmitter supporting clamp carried thereby and comprising two pivotally connected members each having toes to engage the base of the transmitter, one of said members being made in two sections connected by a horizontal pivot whereby the outer section of 105 said two part member can swing outwardly and downwardly.

4. The combination with a bracket, of a transmitter supporting clamp pivotally secured thereto and composed of two pivotally 110 connected members, one of which is made in two sections, the said sectional member adapted to swing outwardly and the outer section of said member adapted to swing downwardly, and a spring for holding said outer section normally in a plane with the other parts of said clamp.

In testimony whereof, I have signed this specification in the presence of two subscribing witnesses.

WILLIAM S. AUNGST.
